Sol Forman, Leonard Ramer, and Arthur Mund,
New York, N. Y., assignors to Forman Family,
Inc., Brooklyn, N. Y., a corporation of New
York

Application June 3, 1950, Serial No. 10,336

Term of patent 3½ years

(Cl. D54—2)

To all whom it may concern:

Be it known that we, Sol Forman, Leonard Ramer, and Arthur Mund, citizens of the United States, residing at New York city, in the county of Kings, Queens, and Queens respectively, and State of New York, have invented a new, original, and ornamental Design for Embossed Metal Sheet or Similar Article, of which the following is a specification, reference being had to the accompanying drawing, forming part thereof.

In the drawing, the single figure is a top view of embossed metal sheet, showing our new design.

The design shown in the drawing is embossed on the top surface of the metal sheeting and the underside of the sheeting is smooth.

We claim:

The ornamental design for an embossed metal sheet or similar article, as shown and described.

SOL FORMAN.
LEONARD RAMER.
ARTHUR MUND.
